DESIGN FOR A COMBINED STATEMENT, SIGNATURE AND CHECK FILE

Sidney S. Goldstein and Jack Lieberman,
New York, N. Y.

Application August 24, 1940, Serial No. 94,602

Term of patent 14 years

To all whom it may concern:

Be it known that we, Sidney S. Goldstein and Jack Lieberman, citizens of the United States of America, residing in New York city, in the county of Bronx and State of New York, have invented a new, original, and ornamental Design for a Combined Statement, Signature and Check File, of which the following is a specification, reference being had to the accompanying drawing, forming part thereof, wherein,

Figure 1 is a front perspective view of a combined statement, signature and check file showing our new design in an opened position.

Figure 2 is a front view thereof in a closed position.

Figure 3 is an end view thereof.

The rear of the combined statement, signature and check file is substantially plain in appearance.

We claim:

The ornamental design for a combined statement, signature and check file, substantially as shown and described.

SIDNEY S. GOLDSTEIN.
JACK LIEBERMAN.
